UNITED STATES PATENT OFFICE.

DELOSS W. JORDAN, OF WATERLOO, IOWA.

CENTRIFUGAL LIQUID-SEPARATOR.

No. 838,718.

Specification of Letters Patent.

Patented Dec. 18, 1906.

Application filed December 13, 1905. Serial No. 291,544.

To all whom it may concern:

Be it known that I, DELOSS W. JORDAN, a citizen of the United States of America, and a resident of Waterloo, Blackhawk county, 5 Iowa, have invented certain new and useful Improvements in Centrifugal Liquid-Separators, of which the following is a specification.

My invention relates to improvements in 10 centrifugal liquid-separators; and the object of my improvement is to provide a centrally-perforated cream-screw for the exit of separated cream or the separated lighter constituent of the liquid so constructed as to permit 15 of the adjustment of the inner opening of said exit to space it nearer to or farther away from the axis of the separator-bowl that liquids having varying degrees of the lighter constituent may thus be properly separated.

20 This object I have achieved by the means which are hereinafter described and claimed, and which are illustrated in the accompanying drawings, in which—

Figure 1 is a vertical transverse axial section of the cover of a centrifugal liquid-separator equipped with my improved cream-screw. Fig. 2 is a side elevation of the cream-screw, on a larger scale, showing its recessed lower end. Fig. 3 is a side elevation in perspective of the incasing-cylinder with the cream-screw inclosed therein; and Fig. 4 is a side elevation of the said cylinder, showing its slotted side.

Similar letters of reference refer to similar 35 parts throughout the several views.

I have shown in Fig. 1 a separator-bowl cover *a* of a common type, but having thinner walls than those which have the cream-screw threaded within their walls. Instead of thus placing the cream-screw *d* I have provided 40 a cylinder *c* for its reception interiorly threaded, said cylinder being affixed to the inner cylindrical periphery *b* of the said cover *a*. This cylinder *c* is slotted, as shown in Fig. 4, 45 and its top is left open and its lower end closed. The slot *f* in said cylinder *c* is so located with reference to the inner periphery of the cover *a* that each one of its vertical edges lies in the same vertical plane which intersects the axis of the bowl.

The cream-screw *d* has the usual driving-slot *e* across its top surface and is provided with a vertical axial perforation extending to the slot *g*. A slot *g* is cut horizontally into the lower side of the cream-screw *d*, as shown 55 in Fig. 2. When the cream-screw has been inserted into the cylinder *c*, as shown in Fig. 3, to a sufficient distance, the slot *g* of said screw allows communication to be established between the slot *f* in the cylinder and 60 the axial perforation in the screw. When it is desired to adjust the entrance of the cream-exit to vary it to or from the axis of the bowl, the cream-screw *d* is but slightly turned forward or back, which brings the edge of the 65 slot *g* nearer to or farther away from the said axis and permits the proper adjustment for varying quantities of cream in the milk.

Having described my invention, what I claim as new, and desire to secure by Letters 70 Patent, is—

1. In a centrifugal liquid-separator, an adjustable exit for the lighter constituent of the liquid, composed of a fixed hollow cylinder with open top and closed bottom, and provided with a lateral slot in communication with the interior hollow, and a plug provided with a lengthwise perforation and rotatably fitted within said cylinder, the lower portion of said plug being slotted to effect communication between said perforation and the said lateral slot in said cylinder.

2. In a centrifugal liquid-separator, an adjustable exit for the lighter constituent of the liquid, composed of an interiorly-threaded 85 fixed hollow cylinder with open top and closed bottom, and provided with a lateral slot in communication with the interior hollow, and an exteriorly-threaded plug provided with a lengthwise perforation and rotatably fitted within said cylinder, the lower portion of the plug being slotted laterally to said perforation.

Signed at Waterloo, Iowa, this 11th day of December, 1905.

DELOSS W. JORDAN.
